(57) **CLAIM**

The ornamental design for an automobile wheel as shown and described.

DESCRIPTION

FIG. 1 is a front elevational view of an automobile wheel in accordance with an embodiment of my new design;

FIG. 2 is a rear elevational view thereof;

FIG. 3 is a top plan view thereof;

FIG. 4 is a bottom plan view thereof;

FIG. 5 is a left side elevational view thereof;

FIG. 6 is a right side elevational view thereof; and,

FIG. 7 is a perspective view thereof.

The lighter grey portions are for the purpose of illustrating unclaimed portions of the automobile wheel that form no part of the claimed design. The broken line indicates the boundary of the claimed design and forms no part of the claimed design.
